UNITED STATES PATENT OFFICE.

BENTON W. STOREY, OF HAILEY, IDAHO.

FENCING-GRIP.

1,399,821.

Specification of Letters Patent. Patented Dec. 13, 1921.

Application filed January 12, 1921. Serial No. 436,855.

To all whom it may concern:

Be it known that I, BENTON W. STOREY, a citizen of the United States, residing at Hailey, in the county of Blaine and State 5 of Idaho, have invented a new and useful Fencing-Grip, of which the following is a specification.

The device forming the subject matter of this application is a clamp of that general 10 type which is applied to wire fencing, during the stretching thereof, and the invention aims to provide a clamp of the type mentioned which will have a secure hold on the fencing, it being possible to disengage 15 the clamp readily, and with equal facility, to apply the clamp to the fencing.

It is within the province of the disclosure to improve generally and to enhance the utility of devices of that type to which the 20 invention appertains.

With the above and other objects in view which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the drawings:—

Figure 1 shows in side elevation, a device constructed in accordance with the invention; Fig. 2 is a detail enlarged from Fig. 1; 35 Fig. 3 is an elevation wherein the structure shown in Fig. 2 is viewed at right angles to the showing of that figure; Fig. 4 is a section on the line 4—4 of Fig. 3; Fig. 5 is a section on the line 5—5 of Fig. 3.

40 In carrying out the invention there is provided a pair of jaws 1 and 2, preferably in the form of bars, the bars being provided with eyes 3, adapted to hold any suitable means for stretching a fence.

45 The bars 1 and 2 carry any desired number of devices for pressing the bars or jaws together on a fence, and since these devices are alike, the description will proceed in the singular number.

50 The numeral 4 denotes, generally a frame, comprising a loop-shaped body 5 having outstanding extensions 6. A foot piece 7 is interposed between the extensions 6 and the bar 1, securing elements 8 passing through 55 the extensions 6 and through the foot piece 7, into the bar 1, to hold the frame 4 there-

on. The side of the bar 2 which is remote from the frame 4 carries a cross arm 9 provided in its outer edge with notches or seats 10.

60 A nut 11 fits closely but slidably in the body 5 of the frame 4 and is supplied with outstanding ears 12, wherein links 14 are pivoted. The links are adapted to receive the ends of the cross arm 9, the ends of the 65 links 14 fitting in the notches or seats 10, as indicated clearly in Fig. 5. A screw 15 is held for rotation in the frame 4 and is threaded into the nut 11. The screw 15 rotates in the outer end of the body 5 of the 70 frame 4, and is provided at its inner extremity with a reduced end 16 journaled in an opening 17 formed in the foot piece 7. Since the foot piece 7 is provided, it is unnecessary to bore the bar 1 for the reception 75 of the end 16 of the screw 15, and, consequently, the bar 1 is not weakened. The reduced end 16 of the screw 15 defines a shoulder 20, which, coöperating with the foot piece 7 limits the inward movement of the 80 screw, outward movement of the screw 15 being prevented by means of a retainer 18, such as a pin, inserted transversely through the screw 15 and coöperating with the end portion of the part 5 of the frame 4. The 85 screw 15 is supplied with a handle 19 of any desired sort.

When the links 14 are disengaged from the cross arm 9, the fence may be inserted between the bars 1 and 2. Then, the links 90 14 are engaged with the ends of the cross arm 9 and received in the seats 11. When rotation is imparted to the screw 15, through the instrumentality of the handle 19, the nut 11 will be backed away from the bar 1, 95 the bar 2 being drawn toward the bar 1, by the links 14 and the cross arm 9, the fence being clamped securely between the elements 1 and 2.

Having thus described the invention, what 100 is claimed is:

1. In a device of the class described, jaws; a frame on one jaw; a cross arm on the other jaw; a nut slidable in the frame; links pivoted to the nut and extended transversely 105 of both jaws, the links being engaged detachably with the cross arm; and a screw threaded into the nut, the screw being held for rotation but against longitudinal movement in the frame.

110 2. In a device of the class described, jaws; a frame; a foot piece interposed between the

frame and one jaw; means for securing the frame and the foot piece to said jaw; a nut 5 slideable in the frame; a screw threaded into the nut, the screw being journaled in the outer end of the frame, and having a reduced end journaled in the foot piece; a retainer carried by the screw and coöperating with the outer end of the frame, to limit the outward movement of the screw; and links

forming a detachable connection between the 10 nut and the other jaw.

In testimony that I claim the foregoing as my own, I have hereto affixed my signature in the presence of two witnesses.

BENTON W. STOREY.

Witnesses:

JAMES J. McFADDEN,
HELENA SNIDER.
